UMBRELLA STAND

Raymond A. Magnuson, Hinsdale, and Robert W. Schier, Northbrook, Ill., assignors to Vogel-Peterson Co., Chicago, Ill., a corporation of Illinois

Filed June 15, 1965, Ser. No. 85,749

Term of patent 14 years

(Cl. D33—17)

We claim:

The ornamental design for an umbrella stand, substantially as shown and described.
